[57] CLAIM

The ornamental design for a nit comb, as shown and described.

DESCRIPTION

FIG. 1 is a top perspective view of a nit comb showing my new design;

FIG. 2 is a side elevational view thereof, the side opposite being a mirror image of the side shown;

FIG. 3 is an end elevational view seen from the right of FIG. 2;

FIG. 4 is an end elevational view seen from the left of FIG. 2;

FIG. 5 is a top plan view thereof;

FIG. 6 is a bottom plan view thereof;

FIG. 7 is an enlarged fragmentary bottom view shown partially rotated to the right of FIG. 6; and

FIG. 8 is a cross-sectional view taken along 8—8 of FIG. 1.
